DESIGN FOR A COMBINATION SPATULA, SPOON, AND SCRAPER

William Paul Ferris, York, Pa., assignor to Ferris
Factories, Inc., York, Pa., a corporation of
Pennsylvania

Application May 7, 1946, Serial No. 129,394

Term of patent 7 years

(Cl. D44—29)

To all whom it may concern:

Be it known that I, William Paul Ferris, a citizen of the United States, residing at York, in the county of York and State of Pennsylvania, have invented a new, original and ornamental Design for a Combination Spatula, Spoon, and Scraper, of which the following is a specification, reference being had to the accompanying drawing, forming part thereof.

In the drawing:

Figure 1 is a perspective view of a combination spatula, spoon, and scraper, showing my new design.

Figure 2 is a side elevation of the same, and
Figure 3 is a front end elevation thereof.

I claim:

The ornamental design for a combination spatula, spoon, and scraper, as shown.

W. PAUL FERRIS.
